DESIGN FOR AUTOMOTIVE VEHICLE HEATER

Harry Rose, Wyandotte, Mich.

Application March 27, 1935, Serial No. 56,077

Term of patent 7 years

To all whom it may concern:

Be it known that I, Harry Rose, a citizen of the United States, residing at Wyandotte, in the county of Wayne and State of Michigan, have invented a new, original, and ornamental Design for Automotive Vehicle Heaters, of which the following is a specification, reference being had to the accompanying drawing, forming part thereof.

Fig. 1 is a front elevational view of an automo-

tive vehicle heater showing my new design with two of the shutter elements in open position; and

Fig. 2 is a side elevational view of the automotive vehicle heater with two of the shutter elements in open position.

I claim:

The ornamental design for an automotive vehicle heater as shown and described.

HARRY ROSE.
